UNITED STATES PATENT OFFICE.

BARTON P. JENKS, OF CONCORD, NEW HAMPSHIRE, ASSIGNOR TO WM. B. DURGIN CO.
OF CONCORD, NEW HAMPSHIRE, A CORPORATION OF NEW HAMPSHIRE.

DESIGN FOR A HANDLE FOR SPOONS, FORKS, OR SIMILAR ARTICLES.

44,207.

Specification for Design.

Patented June 17, 1913.

Application filed April 15, 1913. Serial No. 761,349. Term of patent 14 years.

To all whom it may concern:

Be it known that I, BARTON P. JENKS, a citizen of the United States, residing at Concord, in the county of Merrimack and State of New Hampshire, have invented a new, original, and ornamental Design for Handles for Spoons, Forks, or Similar Articles, reference being had to the accompanying drawings.

Figure 1 is a view of the obverse side of the handle, showing my design. Fig. 2 is a

view of the reverse side of the handle, and Fig. 3 is a perspective view of a portion of the handle, showing my design.

I claim—

The ornamental design for a handle for spoons, forks or similar articles, as shown.

BARTON P. JENKS.
